UNITED STATES PATENT OFFICE.

ALBERT PARTIN AND MARCUS L. STEVENSON, OF ANCHORAGE, TERRITORY OF
ALASKA.

SELF-CLEANING COMB.

Application filed May 27, 1922. Serial No. 564,018.

To all whom it may concern:

Be it known that ALBERT PARTIN and MARCUS L. STEVENSON, citizens of the United States of America, residing at Anchorage, in 5 the Territory of Alaska, have invented new and useful improvements in Self-Cleaning Combs, of which the following is a specification.

The object of the invention is to provide a 10 simple and efficient construction of self-cleaning comb particularly adapted for use as a pocket comb, wherein the teeth are housed or protected when not in use and are cleaned or relieved of accumulations of 15 loose hair, etc., when restored to the housed or portable condition after the comb has been used; and with this object in view the invention consists in a construction and combination of parts of which a preferred embodiment is shown in the accompanying 20 drawings, wherein:—

Figure 1 is a view of the comb with the parts in the folded or inoperative position.

Figure 2 is a similar view showing the 25 teeth of the comb extended or in the operative position.

Figure 3 is a transverse sectional view on the plane indicated by the line 3—3 of Figure 1 showing in dotted lines the extended 30 position of the teeth.

Figure 4 is a longitudinal sectional view showing the means for locking the parts in the operative and inoperative positions.

The device embodies a case or housing 10 35 having one side wall constructed of substantially parallel transverse fingers 11, and mounted in the casing or housing at one edge is a rocker bar 12 carrying the comb teeth 13 which are disposed at intervals corresponding with the spaces between the fingers 40 of the casing or housing and are adapted to swing through said spaces or intervals as the teeth are moved by the turning of the rocker bar from one position to the other,— 45 that is to say from the extended to the folded position or from the folded or inoperative position to the extended or operative position.

In connection with the rocker bar and adjacent to one end of the casing or housing beyond which said bar extends there is employed a locking device which in the construction illustrated consists of a sleeve 14 slidably fitted on the bar and actuated by 50 a coiled spring 15, said sleeve carrying a pin

16 for selective engagement with sockets 17 and 18 when the comb teeth are respectively in the extended and folded positions. The spring serves to hold the pin in engagement with the socket and the disengagement thereof is effected by an outward sliding movement of the sleeve on the rockerbar, said sleeve being provided with a lateral extension or wing 19 to form a proper grip by which the sleeve may be turned to move the 65 comb teeth from one position to the other.

As the teeth swing from the operative or extended position to their position within the casing or housing, and therefore pass between the spaced fingers of the latter, they 70 are progressively stripped or scraped at their sides from their inner toward their outer ends, to thereby strip therefrom any accumulations of hair or the like which may have been acquired during the use of the 75 comb, so that without special manipulation the cleaning of the comb is accomplished by the closing thereof or the return of the comb teeth to their housed or portable position.

Having described the invention, what is 80 claimed as new and useful is:—

1. A comb having a tooth carrying rocker bar and a casing or housing in which said bar is mounted for turning movement to dispose the teeth respectively within or in 85 outwardly projecting relation with the casing.

2. A comb having a tooth carrying rocker bar and a casing or housing in which said bar is mounted for turning movement to 90 dispose the teeth respectively within or in outwardly projecting relation with the casing, the casing being provided with spaced cleaning fingers between which the comb teeth swing in movement into and out of the 95 casing.

3. A comb having a tooth carrying rocker bar and a casing or housing in which said bar is mounted for turning movement to 100 dispose the teeth respectively within or in outwardly projecting relation with the casing, means being provided for securing the said rocker bar in its adjusted positions.

4. A comb having a tooth carrying rocker-bar and a casing or housing in which said 105 bar is mounted for turning movement to dispose the teeth respectively within or in outwardly projecting relation with the casing, means being provided for securing the said rocker bar in its adjusted positions and 110

- consisting of a spring actuated sleeve mounted thereon and having a pin for selective engagement with sockets in the end of the casing.
5. A comb having a tooth carrying rocker bar and a casing or housing in which said bar is mounted for turning movement to dispose the teeth respectively within or in outwardly projecting relation with the casing, means being provided for securing the said rocker bar in its adjusted positions

and consisting of a spring actuated sleeve mounted thereon and having a pin for selective engagement with sockets in the end of the casing, said sleeve being provided with a lateral extension or wing forming a grip.

In testimony whereof they affix their signatures.

ALBERT PARTIN.
MARCUS L. STEVENSON.
